BRUSH MAKING MACHINE

Anton Zahoransky, Todtnau, Germany

Application March 12, 1931, Serial No. 521,918,
and in Germany April 4, 1930

1 Claim. (Cl. 300—8)

This invention relates to improvements in brush making machines and refers more particularly to filling devices of such machines used for anchoring the bristles of the brush in the body thereof with anchor-clips employed.

Brush making machines are known wherein a filling device immovably connected with the machine frame is used for driving anchor-clips into the brush body which is reciprocated, by means of a movable holding device, in and out of contact with said filling device. Owing to the comparatively heavy weight of reciprocating masses it has been impossible heretofore to increase the velocity and consequently the output of such machines.

It is furthermore known to provide the brush making machines with a punching device for making anchor-clips which are fed into the path of a pounder adapted to drive said clips, together with the bristles, into the bores of the brush body. In these machines the guiding plate upon which the pounder is moved is provided with a special groove used as a guide during the feeding movement of said clips. It has been found that the clips often frictionally engage the walls of said groove so that they cannot be moved by usual means into the path of the pounder, thus interrupting the work of the machine.

An object of this invention is to eliminate the above-mentioned drawbacks by providing a brush making machine using anchor-clips for holding the bristles within the brush body, wherein the filling device of the machine is reciprocated with respect to the brush body. Owing to this arrangement the weight of the movable parts is considerably decreased, as compared with the known machines in which the brush body is moved, so that the velocity and the output of the machines are correspondingly increased.

Another object of my invention is to improve the feeding of the anchor-clips into the path of the pounder by eliminating the feeding groove of the guide plate and by arranging the punching device in close proximity to the pounder so that the anchor-clips leaving the pounding device can be immediately carried by the pounder towards the brush body. This arrangement can also be used in brush making machines wherein immovable filling devices are employed.

The above and other objects will appear more clearly from the following detailed description when taken in connection with the accompanying drawings, which illustrate a preferred embodiment of the inventive idea.

Fig. 1 is a fragmentary side elevation of a

filling device constructed in accordance with the invention.

Fig. 2 is a horizontal section along the lines 2—2 of Fig. 1.

Fig. 3 is a detailed view showing the feeding of the anchor-clips to the reciprocating pounder.

Fig. 4 is a view similar to Fig. 2 showing the filling device during the process of fastening the anchor-clips, together with the bristles, in the brush body.

Fig. 5 is a sectional view showing the position of an anchor-clip and a group of bristles after being secured within the brush body.

The device according to this invention may be used in connection with any known means for separating and feeding the bristles and any known means may be employed for reciprocating the filling device, such as cams, crank mechanisms or the like.

In the drawings the machine frame 10 is provided with guides 11 and supports a reciprocating nozzle body 12 firmly connected with a nozzle 13. The nozzle body is connected with a crosshead 14 carrying a lever 15 pivoted at 16 and actuated by means of a cam 17 rotated by the main shaft 18. The nozzle body 12 and the nozzle 13 are provided with a channel 20a and consist of two parts each, the upper part being connected with the lower one by means of pins 19. A pounder 20 is reciprocated within the channel 20 by means of a lever 21 pivoted at 22 on a bracket 23 rigidly attached to the frame 10, said lever being connected to the pounder by rod 24. A second cam 25 rotated by the main shaft 18 is used to actuate the lever 21, a spring 26 keeping the levers 21 and 15 in engagement with the respective cams.

The punching device which is of known construction for making the anchoring clips 27 comprises a casing 28 within which is mounted for reciprocation a puncher (not shown) having a connection 29 to a lever 30 by means of a rod. Rods 31 and 32 are joined to lever 30 and are actuated by a cam surface 33 rotated by the main shaft 18 to oscillate said lever and thereby operate the puncher through the connection 29. A known means for conveying the clips 27, made out of a strip of metal 34, towards the channel 20 are arranged within the casing 28 and since this means forms no part of the present invention further description thereof is unnecessary. Any known means for conveying the bristles into the path of the pounder 20 may also be employed in connection with the filling device.

A guiding plate 35 is secured to the nozzle 110

body 12 by means of screws 36 and receives in the groove 37 thereof the clips 27 emerging from the casing 28, said groove aligning with the channel 20a. Owing to the fact that the plate 35 must 5 constitute an accurate guide for the clips and since it becomes damaged after considerable use, this plate is made interchangeable, so that it can be easily replaced by a new one. According to this invention, the punching device is disposed 10 in close proximity to the channel 37 in which the reciprocating pounder moves as shown in Fig. 3. Owing to this arrangement the clips are fed smoothly and in the right position and they do not interfere with the movement of the nozzle 15 body.

In Figs. 1 and 2 the nozzle 13 and the pounder 20 are shown in their retracted positions relative to a brush body and are ready for the operation of securing the clips within a brush body 38 and 20 when this operation is completed the clips 27 and bristles 39 are secured within the brush body 38 as shown in Fig. 5.

I claim:—

A filling device for brush making machines, comprising in combination, a frame, a nozzle body carried by said frame and having a single channel adapted to hold both a serrated anchor-clip and a bunch of bristles, a reciprocating pounder within said channel for simultaneously moving said anchor-clip and said bunch of bristles through said channel, a guiding plate connected with said nozzle body and having a groove forming a part of said channel, a stationary device for forming serrated anchor-clips fixed to said frame in close proximity to said channel, means connected with said pounder and said anchor-clip forming device for reciprocating said pounder and for operating said anchor-clip forming device, the anchor-clips formed by said device being situated side by side and parallel to said channel, and means feeding said anchor-clips from said device into said groove.
